UNITED STATES PATENT OFFICE.

GEORGE R. WILLIAMS, OF DOVER, NEW HAMPSHIRE.

PRINTING PRESS.

Application filed October 11, 1917. Serial No. 195,917.

To all whom it may concern:

Be it known that I, GEORGE R. WILLIAMS, a citizen of the United States, and a resident of Dover, in the county of Strafford 5 and State of New Hampshire, have invented an Improvement in Printing Presses, of which the following is a specification.

This invention relates to printing presses, and with regard to certain more specific features, to a method and apparatus for printing a variety of sizes of forms and feeding from a continuous web of paper, cloth or like material.

One of the objects of the present invention is to utilize the advantages of light weight and economy of a rotary press for certain operations, together with the advantages of a flat-bed type of unit for other operations.

Another object is to provide a method and apparatus in which the wear and tear on the machine, and the time required for the non-printing portions of the cycle of operations, are reduced to a minimum.

Another object is to provide a simple and durable press operating at high speed, with a maximum flexibility or availability for wide variations in the size of the work and in the number of operations involved.

Another object is to provide an inexpensive and reliable method and apparatus wherein the several steps and operations are so co-ordinated as to minimize the amount of waste material as well as the loss of time and material due to imperfect registration of the several operations on the printed form.

Other objects will be in part obvious and in part pointed out hereinafter.

The invention accordingly comprises the features of construction and operation, combinations of elements, arrangements of parts, steps and sequence of steps which are exemplified in the structure hereinafter described and the scope of the application of which will be indicated in the following claims.

In the accompanying drawings, in which are shown two of various possible embodiments of this invention and a combination thereof,

Figure 1 is a longitudinal elevation illustrating the left side of a rotary printing unit used in conjunction with two units of the flat-bed type. 55

Figure 2 is a similar view of the left side of a rotary printing unit associated with a rotary type of press.

Figure 3 is an enlarged left side elevation of the rotary printing unit illustrated 60 in Figure 1.

Figure 4 is a transverse section on the line 4—4 of Figure 3, showing a front elevation of the rotary printing unit illustrated 65 in Figure 3.

Figure 5 is a right side elevation of said rotary printing unit, viewed from the right of Figure 4.

Figure 6 is a transverse sectional elevation on the line 6—6 of Figure 3. 70

Figure 7 is a section on the line 7—7 of Figure 6, showing a face view of the pawl driving mechanism.

Figure 8 is a section on the line 8—8 of Figure 6, illustrating the frictional brake. 75

Figure 9 is an enlarged side elevation of certain details of the operating crank shown in Figure 5.

Figure 10 is a vertical section on the line 10—10 of Figure 9. 80

Figure 11 is an enlarged left side elevation of a portion of Figure 2, illustrating particularly the mechanism for tripping or separating the elements of the printing couple during the non-printing events of the 85 cycle of operation.

Figure 12 is a transverse sectional elevation on the line 12—12 of Figure 11.

Figure 13 is a transverse sectional elevation on the line 13—13 of Figure 11, illustrating one of the rotary printing couples. 90

Figure 14 is a horizontal section on the line 14—14 of Figure 11, showing in plan the mechanism for discontinuing the tripping device. 95

Figure 15 is a sectional elevation on the line 15—15 of Figure 14, illustrating the operating handle and tripping mechanism associated therewith.

Figure 16 is an enlarged left side elevation of the rotary cutting attachment illustrated in Figure 2. 100

Figure 17 is a left-side elevation of the overthrow-preventing mechanism shown in the upper right-hand portion of Figure 13.

Figure 18 is a vertical section on the line 5 18—18 of Figure 17.

Figure 19 is a schematic left side elevation showing diagrammatically only the relative positions of the forwarding crank, forwarding rack, and associated parts at 10 the beginning of the first or forwarding event.

Figure 20 is a similar right side elevation of the return crank, return rack, and associated parts at the beginning of said forwarding event.

Figure 21 is a left side elevation of the forwarding pawl and ratchet device shown in Figure 17, illustrating the positions of the several parts at the beginning of the first 20 or forwarding event; and in dotted lines the position of the pawl at the end of this event.

Figure 22 is a right side elevation (looking through the machine) of the return pawl 25 and ratchet device showing the several parts in their relative positions at the beginning of the first or forwarding event; and in dotted lines the position of the pawl at the end of this event.

Figure 23 is a diagrammatic left side elevation of the cutting device of Figures 2 and 16, showing the parts at the beginning of the first or forwarding event.

Figure 24 is a similar view of the same 35 parts at the end of the first third of this event, showing one section of paper cut from the web.

Figure 25 is a similar view of the parts 40 in the position they occupy at the end of the forwarding event, showing three sections cut from the web.

Figure 26 is a similar view of the parts at the end of the return event.

Figure 27 is a view showing in a general 45 way a press embodying features of both of the above modifications.

In considering this invention in its relation to the prior art, it may be noted that for many years attempts have been made 50 to provide roll-feed rotary or cylinder printing presses available for adjustment to a variety of lengths and widths of forms, as well as for a varying number of operations upon each form, without prohibitive weight 55 or initial cost. For some of the printing operations, a flat-bed type of press has been found best suited; for others, a rotary press; and it often happens that the operations to be performed upon a single form can be most 60 expeditiously effected by the use of a press embodying both flat-bed and rotary units. Furthermore, some operations auxiliary to printing, such as scoring or creasing, punching and cutting, can be best performed by 65 the use of reciprocating units, while for

others the rotary style is more economical or more accurate or better adapted to the required speed of operation. In combining the flat-bed or reciprocating units, both printing and auxiliary, with rotary units, 70 both printing and auxiliary, a number of difficulties have arisen, such as cost of construction or maintenance, low speed due to weight of moving parts, loss of time in effecting gear changes during the cycle of operation, and lack of accurate registration of the several operations upon the web. Furthermore, in prior apparatus and methods the rotary printing units have not been adaptable to widely varying sizes of work 75 80 without tedious and expensive adjustments and replacement of parts, or undue waste of material during printing. As the description progresses, it will be seen that in the present invention, the above defects and 85 limitations of prior apparatus and methods are eliminated, and that the present-day requirements for flexibility, high speed, and economy, are adequately met.

Referring now to the accompanying drawings, and more particularly to Figure 1 thereof, there is illustrated a longitudinal elevation of the left side of a printing press whose component parts or units may be designated generally as a mounting 1 for the roll 2 of paper; a feed device 3 through which the web is fed to the first flat-bed printing unit 5; a second flat-bed printing unit 6; a rotary printing unit 8; the punching or cutting and creasing unit 9; and cutting unit 10; the units 5, 6, 8, 9 and 10 being mounted upon a main frame 11. The several printing units may operate on the same portions of the web, or on different portions.

Power for operating the press is derived from a source (not shown) through a pulley and associated gearing to the shaft 12 carrying fly wheel 13. This mechanism between the source of power and the fly-wheel 110 shaft is omitted in order to simplify the drawings, since said mechanism per se forms no feature of the present invention.

From the fly-wheel shaft 12 power is transmitted through the gearing 14, 15 and 115 16 to the gear 17, on which there is adjustably mounted a crank 19, which, for reasons hereinafter set forth, will be referred to as the forwarding crank. This crank in turn serves to oscillate the forwarding connecting rod 20, to communicate an oscillating motion to the forwarding segmental gear 21 meshing with a horizontal forwarding rack 23, supported upon brackets 24 carried upon a main frame 11 of the machine. Continuous rotation of the forwarding gear 17 thus serves to impart to the forwarding rack 23 a reciprocation longitudinally of the apparatus, through a distance determined by the adjusting mechanism indicated at 26. 125 130

and illustrated more in detail in Figures 9 and 10, hereinafter described.

From the forwarding rack 23, motion is communicated to the printing couple 36, 37 of the rotary printing unit 8. A pinion 61 (Figures 4 and 6) driven by the forwarding rack, is keyed to the disc 62 upon which the disc 63 is secured by means of the bolts 64 fitting in segmental slots 65, Figure 7, to provide for a limited relative angular adjustment of the discs 62 and 63. The latter disc carries oppositely disposed pawls 67, which, when driven in a clockwise direction in Figure 1 and a counter-clockwise direction in Figure 7, serve to drive through teeth 68 of a disc 70 keyed to the shaft 71 upon which is mounted the plate cylinder 36. The shaft 71 is carried by bearings 72 in the brackets 25 of the side frames of the machine, and is manually adjustable by the hand-wheel 81. The shaft imparts rotation to the impression cylinder 37 through the gear 74 keyed to the shaft 71, meshing with a gear 75 keyed to the shaft 77 upon which the impression cylinder 37 is mounted.

The shaft 77 is mounted in eccentric bushings 78 carried in the side frames of the machine, and by means of the screws 80 passing through segmental slots (not shown) in the bushings and secured in the side frames of the machine, a limited angular adjustment of the bushings is provided in order to obtain an accurate adjustment of the vertical distance between the impression cylinder 37 and the plate 38 carried on the plate cylinder 36.

A band brake 82, shown in Figure 6 and in detail in Figure 8, serves to prevent overthrow of the printing couple 36, 37, by exerting a pressure upon the hub of the gear 74, above mentioned. The tension of the brake band against the gear 74, and hence the power exerted by the brake upon the shaft 71, may be varied by the adjusting means indicated at 84.

The mechanism comprising the forwarding crank 19 and forwarding rack 23 is substantially duplicated on the right side of the machine, where parts associated with the return event of the cycle of operations are provided, comprising the return crank 44 and return rack 47, illustrated in Figures 4 and 5.

A set of ratchets and pawls associated with the return rack 47 serves to connect the rack with the printing couple 36, 37, during the return event of the cycle of operations, that is, while the forwarding rack 23 is moving toward the right in Figure 1 out of driving engagement with the cylinders 36, 37. The rotation imparted to the cylinder 36 is in the same direction as in the forwarding event (counter-clockwise in Figure 5, clockwise in Figure 1), and the adjustment of the stroke or throw of the re-

turn rack 47 is such that the rack imparts to the cylinders 36, 37, an angular displacement equal to the difference between 360° and the displacement of these cylinders during the forwarding event. That is, if the cylinders travel 60° during the forwarding or paper-feeding event, due to the adjustment of the stroke of the forwarding rack 23, then the return rack 47 is set to give this printing couple a rotation of 300° during the return event, thereby leaving the printing couple in position for the beginning of the next forwarding event. Or the rotation of the printing couple may be 180° or some other angle during each cycle of operations; and this angle may be divided as desired into forwarding and return rotations of any suitable ratio.

The driving connection between the return rack 47 and the printing couple 36, 37, comprises a pinion 86 meshing with the return rack 47 and keyed upon a disc 87 carrying a second disk 89 angularly adjustable with respect to the disc 87 by means of segmental slots and bolts 90 passing therethrough and into the disc 87, to lock the discs 87, 89 together in the desired adjustment. Upon the second disc 89 are pawls 91 which engage and rotate during the return stroke a disc 92 similar to the disc 70 (Figure 7) and provided with teeth or notches (not shown) similar to the teeth 68. This toothed disc 92 is pinned or keyed as at 93 to the shaft 71 carrying the plate cylinder 36, as above described. It will thus be seen that during the return event, when the return rack 47 is traveling upwardly, the counter-clockwise rotation (Figure 5) of the pinion 86 meshing with this rack 47 causes a counter-clockwise rotation of the discs 87 and 89, thence through the pawl and ratchet mechanism, a counter-clockwise rotation (Figure 5) of the plate cylinder 36, to effect the desired extent of rotation of the latter. This counter-clockwise rotation of the cylinder 36 causes a clockwise rotation (Figure 5) of the impression cylinder 37 through the gearing 74, 75, and associated parts described above in connection with the forwarding event.

For convenience in considering the structural features of this embodiment of the invention and the relation of the several parts of the apparatus, the cycle of operations may be divided into two events: a first or forwarding event, during which the paper is fed toward the right in Figure 1 and some of the printing and auxiliary operations are effected; and a second or return event, during which the remaining operations take place.

The first or forwarding event is utilized for feeding the paper toward the right in Figure 1, that is, toward the front of the machine, from the supply roll 2 through the

feeding device 3, printing units 5, 6, and 8, and punching or cutting and creasing unit 9, to the cutting unit 10, where the web is cut into suitable lengths or rewound. During this forwarding or paper-feeding event the platen 28 and bed 29 of the first flat-bed printing unit 5 are separated from one another by mechanism indicated generally at 30, so that the paper passes through toward the right. Likewise the platen 32 and bed 33 of the second flat-bed printing unit 6 are separated by the mechanism indicated generally at 34, so that the paper likewise passes freely through this unit. At the rotary printing unit 8, however, the plate cylinder 36 and impression cylinder 37 are in operative contact, so that during this event the paper passes through in a direction toward the right, and the printing to be performed in this unit 8 is effected.

As the several units 5, 6, and 8 are shown in Figure 1, the flat-bed units 5 and 6 are adapted to print on the top of the web, while the rotary unit 8 prints on the under side of the web. The relative arrangement of the several units, however, is of course optional and depends upon the character of the work to be performed.

The printing units 5 and 6 are relatively adjustable longitudinally of the web by being mounted on the guides 39; suitable means (not shown) being provided to lock the units securely in their adjusted positions. Likewise the units 8, 9 and 10 are adjustable longitudinally of the web by being mounted upon tracks 40, with appropriate locking devices 41.

From the above it will be seen that during the forwarding event the paper passes idly through the flat-bed printing units 5 and 6, and is printed upon during its passage through the rotary unit 8.

At the end of this first or forwarding event the paper is brought to rest by the stopping of the feed rolls 42 mounted in the cutting unit 10 and driven from the forwarding rack 23 through suitable gearing and pawl and ratchet mechanism, which is omitted in order to simplify the drawings.

The forwarding rack 23 stops its forwarding or leftward motion at this time, because the forwarding crank 19 from which this rack is driven has reached the leftward end of its travel (Figures 1 and 3). Owing to the pawl and ratchet drive of the feed rolls they do not become again operative to advance the paper rightward, until the next leftward movement of the forwarding crank 23, which occurs during the next forwarding event.

Simultaneously with the stopping of the feed rolls 42 and forwarding rack 23, the plate 36 and impression cylinder 37 stop rotating. During the second or return event, the forwarding rack 23 is moving toward

the right in Figure 1, and is disconnected from the plate 36 and cylinder 37. By arranging the return crank 44 so that its stroke will be timed oppositely to the stroke of the forwarding crank 19, the return rack 47 will act through its pawl and ratchet mechanism to rotate the plate 36 and cylinder 37 during the return stroke only, and it is during this return stroke that the printing couple 36, 37 is given the proper extent of rotation to bring it into position for the next printing operation, which occurs during the next forwarding event. That is, if 60 of the 360° of the plate 36 carry type or other matter to be printed, then a 60-degree rotation is imparted to the printing couple 36, 37 by the leftward movement of the forwarding rack 23 through its pawl and ratchet mechanism during the forwarding stroke; and the remaining 300 of the 360 degrees of rotation is imparted to the printing couple 36, 37 by the return rack 47 through its pawl and ratchet mechanism upon its rightward movement during the return event.

The device above indicated for adjusting the stroke of the crank 19 is indicated generally by the reference character 26 in Figure 1. This is a counterpart of the mechanism 48 as shown in Figures 4, 5, 9, and 10 for adjusting the stroke of the return rack 47. The device 48 comprises a guide 49 for a sliding block 50 provided with an aperture to receive a bolt 51, which is mounted in a head piece or bracket 52 for rotation therein without reciprocation. The rotation of the bolt 51 thus serves to adjust the eccentricity of the crank 44. In order to lock the crank 44 in its adjusted position, the nut 53 is tightened to draw the sliding block 50 outwardly (toward the right in Figure 10) wedging it against the guide 49. The thimble 54 spaces the nut 53 and the washer 55 from the outer face 56 of the block 50, thus providing between the washer 55 and the shoulder 58 of the thimble, a free bearing in which the return rack 47 is mounted. The guide 49 is bolted to the disc 59, which in turn is keyed to the shaft 60 carrying the gear 17. This return rack 47 is driven from a return gear 57 similar to the forwarding gear 17 and driven from the flywheel shaft 12 through a pinion similar to the pinion 14 meshing with the gear 57. The pinions 17 and 57, are mounted upon the same shaft 60.

The inking of the plate 38 on the cylinder 36 is effected by means of the inking rollers 95 (Figure 5), each contacting with the plate 38 during the non-printing portion of its rotation, and each contacting likewise with the larger inking roller 96, which in turn receives its ink from a fountain (not shown) through suitable means such as a series of rollers, of which three are indicated diagrammatically at 98.

Co-operating with the impression cylinder 37 are a series of rolls 100 indicated diagrammatically in Figure 5. As these are the type of rolls ordinarily employed in the art, they are not illustrated or described in detail.

Referring now to the modification illustrated in Figures 2 and 11 to 26 of the drawings, there is shown an apparatus utilizing 10 a series of units all of the rotary type. In Figure 2 is a longitudinal elevation of the left side of the press, whose component parts or units may be designated generally as a supply unit, printing units, and auxiliary 15 units, including a cutting device. The web is delivered from a mounting 201 for the roll 202 of paper, to a feed device 203 through which the web is fed to the rotary printing unit 205, which may be referred to as a face 20 printing unit because it is arranged to print on the top or face of the web. The web is passed from this first unit 205 to the second 25 rotary face printing unit 206, and thereafter through the under-side rotary printing unit 208, arranged to print on the bottom or under-side of the web. From this unit 208 the web is passed in succession through the rotary punching unit 209, scoring or creasing unit 207, feeding unit 204, and cutting 30 unit 210, all of the rotary type and all mounted upon a main frame 211. Power for operating the press is derived from a source, not shown, through a pulley and associated gearing, to the shaft 212 carrying fly-wheel 213. 35 This mechanism between the source of power and the fly-wheel shaft is omitted, in order to simplify the drawings, since said mechanism per se forms no feature of the present invention.

40 From the fly-wheel shaft 212 power is transmitted through the gear 214 to the gear 217, on which there is adjustably mounted a forwarding crank 219. This crank in turn serves to oscillate the forwarding connecting 45 rod 220 through which an oscillating motion is communicated to the link 221 carrying the sliding box 222 which in turn reciprocates the horizontal forwarding rack 223, supported upon brackets 224 carried upon the 50 main frame 211 of the machine. Continuous rotation of the forwarding gear 217 thus serves to impart to the forwarding rack 223 a reciprocation longitudinally of the apparatus, through a distance determined by 55 the adjusting mechanism indicated at 226. This adjusting mechanism is illustrated more in detail in Figures 19 and 20, and is similar to the adjusting mechanism shown in Figures 9 and 10 above described. Briefly, this 60 adjusting mechanism comprises a guide 249 for a sliding block 250 provided with an aperture to receive a bolt 251 which is mounted in a head-piece or bracket 252 for rotation therein without reciprocation. The rotation 65 of the bolt 251 thus serves to adjust the eccentricity of the crank 244. In order to lock the crank 244 in its adjusted position, the nut 253 is tightened to draw the sliding block 250 outwardly, wedging it against the guide 249.

A thimble similar to the thimble 54 of Figure 10 spaces the nut 253 and the washer 255 from the outer face of the block 250, thus providing between the washer 255 and the shoulder of the timble, a free bearing in which the forwarding connecting rod 233 is mounted. The guide 249 is bolted to the disc 259, which in turn is keyed to the shaft 260 carrying the gear 217.

Motion is transmitted from the forwarding connecting rod 220 to the link 221, which is provided with longitudinal or radial tongues 302 forming guides for the slotted block 222, in which a stud 303 is journaled so that angular movement of the link 221, caused by movement of the connecting rod 220, compels the sliding block 222 and stud 303 to partake of the same extent of angular movement about the pivot 304 of the link 221, but permits an up-and-down sliding movement of the block 222 and stud 303 90 radially of the link 221. This radial movement of the stud 303 with respect to the link 221 is determined by the travel permitted to the block 306 upon which the stud 303 is mounted. This latter block is slidably 95 mounted in the yoke or bracket 307 bolted to the bracket 224 above described. A face plate 309, screwed to the yoke 307, retains the horizontal block 306 in position within the yoke. The block 306 may be mechanically 100 considered as a part of the forwarding rack 223, since as indicated in Figure 11, this rack 223 is constructed in sections extending in either direction from the horizontally sliding block 306, to which the sections are secured 105 by suitable means such as the screws 311. With this construction, the rotation of the forwarding crank 219 oscillates the link 221 through the connecting rod 220, causing the horizontal reciprocation of the block 306 and forwarding rack 223, the power being transmitted through the sliding block construction, which affords certain advantages in mechanical strength as compared with the segmental gear 21 of Figure 1.

110 From the forwarding rack 223 motion is communicated to the printing couples of the several printing units 205, 206 and 208. Taking the first of these units 205 for example, there is provided a pinion 261 (Figure 13) driven by the forwarding rack 223 and keyed to the disc 262 upon which the disc 263 is secured by means of the bolt 264 fitting in segmental slots similar to the slots 65 of Figure 7, to provide for a limited relative angular adjustment of the discs 262 and 263. The latter disc carries oppositely disposed pawls 267 which when driven in a counter-clockwise direction (Figures 2 and 11) serve to drive through teeth similar to 120 125 130

- the teeth 68 of Figure 7, a disc 270 keyed to the shaft 271 upon which is mounted the plate cylinder 236. Two teeth are preferred instead of a larger number, in order to minimize or prevent any danger of overthrow of the printing couple. A single tooth would serve for certain purposes, but would give less flexibility of adjustment, and less balanced mechanical strains, than two teeth.
- 10 The shaft 271 is carried by bearings 272 in the side frames of the machine, and imparts rotation to the impression cylinder 237 through the gear 274 keyed to the shaft 271, meshing with a gear 275 keyed to the shaft 15 277 upon which the impression cylinder 237 is mounted.
- The shaft 277 is mounted in eccentric bushings 278 carried in the sliding boxes 301 of the tripping mechanism hereinafter described. By means of screws similar to the screws 80 of Figure 6, passing through segmental slots in the bushings 278 and secured in the sliding boxes 301, a limited angular adjustment of the bushings is provided in order to obtain an accurate adjustment of the vertical distance between the impression cylinder 237 and the plate 238 carried on the plate cylinder 236.
- In order to prevent overthrow of the printing couple 236, 237, a pair of studs 227 slidably mounted in the ratchet-carrying disc 270, may be pushed toward the left in Figure 18, into holes 228 in the pawl-carrying disc 263 during the forwarding event 30 of the cycle of operations. But since the power for operating this overthrow-preventing mechanism is derived from a longitudinal bar 327 not yet described, the details of this device will be referred to hereinafter.
- 35 A band brake 282, shown in Figure 13, similar to the brake illustrated in detail in Figure 8, serves to prevent overthrow of the printing couple 236, 237, by exerting a pressure upon the disc 273 keyed to the shaft 271. The tension of the brake band against the disc 273, and hence the power exerted by the brake upon the shaft 271, may be varied by adjusting means similar to the means indicated at 84 in Figure 8.
- 40 In order to maintain the forwarding rack 223 in its proper relation to the gear 261 meshing therewith, a shoe 297 (Figure 13) is provided as a track or guide for the under side of the rack 223, and this shoe is adjustably secured in the desired vertical position by means such as the set screws 299.
- The mechanism comprising the forwarding crank 219, connecting rod 220, link 221, sliding box 222 and forwarding rack 223 is 45 duplicated on the right side of the machine, where parts associated with the return event of the cycle of operations are provided, comprising the return crank 244, return connecting rod 243, return link (not shown), return sliding box (not shown) and return 50 rack 247, illustrated in Figures 13 and 18. The return rack 247 is driven from a return gear 257 similar to the forwarding gear 217 and driven from the fly-wheel shaft 212 through a pinion similar to the pinion 214 meshing with the gear 257. The pinions 217 and 257 are mounted upon the same shaft 260.
- A set of ratchets and pawls associated with the return rack 247 serves to connect the rack with the printing couple 236, 237 during the return event of the cycle of operations, that is, while the forwarding rack 223 is moving toward the left in Figure 2 out of driving engagement with the printing couple 236, 237. The rotation imparted to the couple is in the same direction as in the forwarding event, and the adjustment of the stroke or throw of the return rack 247 is such that the rack imparts to the cylinders 236, 237, an angular displacement equal to the difference between 360° and the displacement of these cylinders during the forwarding event. That is, if the cylinders travel 300° during the forwarding or paper-feeding even, due to the adjustment of the stroke of the forwarding rack 223, then the return rack 247 is set to give this printing couple a rotation of 60° during the return event, thereby leaving the printing couple 95 in position for the beginning of the next forwarding event. Or the rotation of the printing couple may be 180° or some other angle during each cycle of operations; and this angle may be divided into any suitable 100 ratio of forwarding and return movement.
- A shoe 312, similar to the shoe 297, above described, preserves a proper meshing relation between the return rack 247 and the gear 286, by serving as a track or guide for the under side of the rack, as indicated in Figure 13. By means of set-screws 313, this shoe is maintained at the desired height.
- The driving connection between the return rack 247 and the printing couple 236, 237, comprises a pinion 286 meshing with the return rack 247 and keyed upon a disc 287 carrying a second disc 289 angularly adjustable with respect to the disc 287 by means of segmental slots and bolts 290 115 passing therethrough and into the disc 287, to lock the discs 287, 289 together in the desired adjustment. Upon the second disc 289 are pawls 291 which engage and rotate during the return stroke, a disc 292 (Figure 120 22) similar to the disc 70 in Figure 7, and provided with teeth or notches (not shown) similar to the teeth 68. This toothed disc 292 is pinned or keyed as at 293 to the shaft 271 carrying the cylinder 236, as 125 above described. It will thus be seen that during the return event, when the return rack 247 is traveling toward the left in Figures 2 and 19 (toward the right in Figure 20), the rotation of the pinion 286 mesh- 130

ing with this rack 247 causes a rotation of the discs 287 and 289, thence through the pawl and ratchet mechanism, a rotation of the plate cylinder 236, to effect the desired extent of rotation of the latter. This rotation of the plate cylinder 236 causes rotation of the impression cylinder 237 through the gearing 274, 275 and associated parts described above in connection with the 10 forwarding event.

The inking of the plate 238 on the cylinder 236 is effected by means of the inking rollers 295 (Figure 11), each contacting with the plate 238 during the non-printing 15 portion of its rotation, and each contacting likewise with the larger inking roller 296, which in turn receives its ink from a fountain (not shown) through suitable means such as a series of rollers, of which three 20 are indicated diagrammatically at 298.

For convenience in considering the structural features of this embodiment of the invention and the relation of the several parts of the apparatus, the cycle of operations may be divided into four events; a 25 first or forwarding event, during which the paper is fed toward the right in Figure 2 and the various printing and auxiliary operations are effected; a second or tripping event, during which the printing couples are separated by the tripping mechanism 30 hereinafter described; a third or return event, during which the idle movement of the printing couples takes place, the web 35 remaining stationary; and a fourth or re-engaging event, during which the printing couples are again brought into operative contact for the succeeding cycle of operations.

40 During the first or forwarding event the paper is fed toward the right in Figure 2, that is, toward the front of the machine, from the supply roll 202 through the feeding device 203, printing units 205, 206 and 45 208, punching unit 209, creasing or scoring unit 207, and feeding unit 204, to the cutting unit 210 where the web is cut into suitable lengths. During this forwarding event the printing couples of the several printing 50 units 205, 206, 208 are in operative contact, so that during this event the printing is effected.

As the several units 205, 206, 208 are illustrated in Figure 2, the first two are adapted 55 to print on the face or top of the web, while the third unit, 208, prints on the under side of the web. The relative arrangement of the several units, however, is of course optional and depends upon the character of 60 work to be performed.

The several units 205, 206, 208, 209, and 65 the apparatus or unit comprising the auxiliary devices 207, 204 and 210, are relatively adjustable longitudinally of the web by being mounted on tracks 240 with appro-

priate locking devices 241. For convenience in adjusting these units a crank 315 is mounted at the forward end of the machine, as indicated in Figure 2, and is connected to a threaded rod 316 running lengthwise 70 of the apparatus to a bearing 318 at the rear. By closing clutches (not shown) associated with the several units, the rotation of the crank 315 and rod 316 serves to adjust one or more of the units along the 75 tracks 240 to vary the distance between the units and thus effect the desired registration of the several operations upon the web.

The operations performed upon the web at the auxiliary units 209, 207 and 210 during this first or forwarding event will be described hereinafter.

At the end of this first or forwarding event the paper is brought to rest by the stopping of the feed rolls 204 mounted in 85 the cutting unit 210 and driven from the forwarding rack 223 through suitable gearing and pawl and ratchet mechanism, which is omitted in order to simplify the drawings. The forwarding rack 223 stops its forward- 90 ing or rightward motion at this time, because the forwarding crank 219 from which this rack is driven has reached the leftward end of its travel (Figure 2). Owing to the pawl and ratchet drive associated with 95 the feed rolls, they do not become again operative to advance the paper rightward, until the next rightward movement of the forwarding crank 223, which occurs during the next forwarding event.

Upon the completion of the forwarding event the tripping mechanism is brought 100 into play and serves to separate or disengage the printing couples such as the cylinders 236, 237 of the printing unit 205, to permit 105 the rotation of the printing couples through the idle part of their movement during the third or return event. This tripping mechanism is part of the apparatus shown in Figure 2, but is omitted from Figure 2 in 110 order to simplify the drawings. The mechanism is indicated in left side elevation in Figure 11, in transverse sectional elevation in Figures 13 and 15, and in plan in Figure 14.

The tripping mechanism is driven from 115 the shaft 260, which, as above described, is rotated continuously from the fly-wheel shaft 212 and carries the forwarding gear 217 and return gear 257 for driving the forwarding and return racks 223, 247, respectively. Upon this shaft 260 is keyed a cam 320 whose rotation in a counter-clockwise direction (Figure 11) reciprocates the rollers 321 carried upon a cam connection 323 120 which in turn is slidably mounted upon the block 324 journaled upon the shaft 260. The cam 320 is so proportioned that its rotation imparts to the cam connection 323 first a 125 quick rightward movement, and then after 130

a period of rest, a quick leftward movement, followed by another period of rest. The cam positively drives the cam connection in both directions, to insure accuracy and proper timing of the operations resulting from or effected by this movement.

The reciprocation of the cam connection 323 oscillates the bell-crank 326, which in turn effects a reciprocation of the operating bar 327 running lengthwise of the press and connected to perform simultaneously the tripping operations in the printing units 205, 206 and 208 upon the completion of the first or forwarding event. The horizontal component of the motion of this rod 327 may be disregarded, since it is only the vertical component that is utilized. Furthermore, this rod has no connection with the auxiliary units 209, 207, 204 or 210, which are driven only from the forwarding crank 223, and are operated during the forwarding event only.

The vertical reciprocation of the operating bar 327 effects at each of the printing units 205, 206 and 208 the vertical reciprocation of a yoke 329 (Figures 13, 14 and 15), which causes the rocking member 330 to oscillate. It will thus be seen that throughout the operation of the apparatus this rocking member 330 is given a quick rotation of slight angular extent in one direction, and then after a period of rest, a similar quick rotation in the opposite direction, followed by a second period of rest; and this cycle occurs once during each cycle of operations of the apparatus. The cam 320 is so timed that the rocking member 330 is at rest during the first or forwarding event, rotates clockwise (Figures 11 and 15) during the tripping event, is again at rest during the return event, and rotates counter-clockwise during the fourth or re-engaging event.

The quick rotation of the rocking member 330 clockwise during the tripping event is communicated to the impression cylinder 237 (Figure 11) to move the latter vertically downward. For this purpose the rocking member 330, which is loosely mounted on the rock shaft 332, carries an extension 333 (Figures 14 and 15) centrally apertured to receive a sliding pin or locking bolt 334, which in its rightward position (upward in Figure 14 and toward the rear in Figure 15) locks the rocking member 330 to the U-shaped fork 336 keyed as at 337 to the rock shaft 332 above described. A handle 338, double-ended as indicated in Figures 14 and 15 for convenience in operation, is pivotally mounted upon the fork 336 by means of the stud 339, and is operatively connected as at 341 to the sliding bolt 334, a spring-pressed plunger or detent 342 thereon co-operating with the notches 343 in the fork 336 to lock the handle in any one of its three operative positions. With

the handle toward the right, that is, at the upper limit of its travel as illustrated in Figure 14, the sliding bolt 334 shifted thereby connects the rocking member 330 to the fork 336, so that the periodic oscillations of the rocking member are communicated to the fork and thence to the rock shaft 332. Mounted upon either end of this rock shaft 332 is a crank 345 connected by links 346 to the sliding boxes 301 above mentioned in connection with the eccentric bushings 278. The crank 345 and links 346 approach a straight-line position as the cranks move counter-clockwise in Figures 11 and 15, forming a toggle which insures both strength and accuracy in raising the sliding boxes 301 to their uppermost position, corresponding to the printing position of cylinders 236, 237 of the printing couple. It will thus be seen that with the handle 338 in this rightward position, that is, upward in Figure 14, the sliding bolt 334 connects the rocking member 330 to the fork 336 and through the toggle mechanism 345, 346 imparts to the sliding boxes and impression cylinder 237 a quick downward movement during the tripping event to separate this cylinder from the plate cylinder 236 and thereby permit the rotation of the two cylinders 236, 237 of the printing couple during the third or return event, while the paper is held stationary, without danger of contact between either cylinder and the paper. During the fourth or re-engaging event the rocking member 330 is given a quick oscillation counter-clockwise in Figures 11 and 15, thereby raising the sliding boxes 301 and impression cylinder 237 to restore the printing couple 236, 237 to operative or printing position, ready for the printing during the first or forwarding event of the next cycle of operations. The teeth of gears 274, 275 are long enough to remain in mesh when the cylinder 237 is lowered.

The above sequence of operations occurs automatically whenever the handle is in its rightward position illustrated in Figure 14, and this position of the handle may therefore be referred to for convenience as the normal or operating or automatic position. If the handle be shifted to the middle or neutral of its three positions, the sliding bolt 334 will be moved out of the aperture in the extension 333 of the rocking member 330 so that the rocking of the latter will impart no movement to the fork 336, sliding boxes 301, or impression cylinder 237. The weight of the boxes 301 and impression cylinder 237 ordinarily causes them at this time to drop to the inoperative or non-printing position that they occupy during the third or return event. This facilitates the various adjustments that may be needed prior to the operation of the apparatus, such as changing of the plates, and the threading of the web.

With the handle in this middle or neutral position, the impression cylinder may be raised and lowered manually.

The handle 338 in its third or leftward position, that is, downward in Figure 14, locks the sliding boxes 301 and impression cylinder 237 in their uppermost or printing position, because at this time the sliding bolt 334 is in an aperture 348 in the frame of the apparatus, this aperture being so positioned that the bolt 334 is in register therewith when the sliding boxes 301 are at the upper limit of their travel, corresponding to the position they occupy during the first or forwarding event of the cycle.

The mechanism previously mentioned for preventing overthrow of the printing couple 236, 237, during the forwarding stroke of the cycle of operations, is illustrated in the upper right-hand portion of Figure 13, and in detail in Figures 17 and 18. The power for operating this mechanism is derived from the central horizontal longitudinal bar 327, associated with the tripping mechanism, and which as above described is automatically raised at the beginning of the forwarding stroke and automatically lowered at the end of said stroke. Mounted upon the yoke 329 driven from this bar 327 is a link 372 pivoted to a bracket 373 secured to the rock shaft 374 carrying adjacent its outer end a second bracket 375 to which is pivotally connected the universal joint 376 which serves to transmit motion from the bracket 375 to the bracket 377 pinned to the upper rock shaft 378. It will thus be seen that the upward movement of the bar 327 at the beginning of the forwarding event effects a counter-clockwise rotation of the upper rock shaft 378, and that the downward movement of the bar 327 at the end of the forwarding stroke causes a clockwise motion of this upper rock shaft 378. A rock arm 379 pinned to this upper rock shaft transmits motion to the yoke 380 through a stiff spring 381, seated in the rock arm 379 and in a cross piece 382 of the yoke. The yoke is journalled at its lower end upon the upper rock shaft 378 and at its upper end is pivotally secured at 383 to the sliding ring or sleeve 384 in which are mounted the studs 227, which as previously described pass through the ratchet-carrying disk 270 and are adapted to enter apertures (Figure 18) 228 in the pawl-carrying disc 263 during the forwarding event, to lock the disc 270, 263 positively together and thus prevent any overthrow that might otherwise occur if the only connection between these discs were the pawl-and-ratchet drive 267, 268.

It will be seen that the upward movement of the central longitudinal bar 327 at the beginning of the forwarding event causes the link 372 to move upwardly; this in turn rotates the lower rock shaft 374 and bracket

375 clockwise (Figure 17), moving the universal joint 376 upward, and rotating in a counterclockwise direction (Figure 18) the bracket 377, upper rock shaft 378, rock arm 379 and yoke 380, causing the sliding ring 384 and pins 227 to be shifted toward the left in Figure 18, to cause the latter to enter the apertures 228 in the pawl disc 263, as indicated in Figure 18. That is, of course, on the assumption that at this time the holes 228 are in registration with the pins 227, and this will ordinarily be the case, because the holes are so located as to be in registration with the pins whenever the pawls 267 are in proper engagement with the ratchet 268. If, however, the holes 228 are not in position to receive the pins 227, no harm will be done, because the safety spring 381 between the rock arm 379 and the yoke 380, will simply be compressed. At the end of the forwarding stroke, the bar 327 is automatically lowered, as previously described, and this causes the pins 227 to be moved toward the right in Figure 18, and thus automatically withdrawn from the pawl disc 263. It is thus impossible for the momentum of the printing couple to carry the ratchet ahead of the pawl.

Mechanism similar to the above may be provided in connection with the return stroke, but in order to simplify the drawings, such an embodiment of the invention has not been illustrated. The band brake 282 will ordinarily be found adequate to prevent any undesirable overthrow of the printing couple during the return stroke.

From the third printing unit 208 the web passes through a punching unit 209 comprising primarily the punch and die cylinders 350, 351, connected together by a suitable gearing (not shown) and driven through a pawl and ratchet mechanism (not shown) from the forwarding rack 223 during the rightward movement of the latter. The rotation of the punching members thus occurs only during the paper-feeding movement, and the extent of rotation of these members depends upon the stroke of the forwarding rack 223, which in turn is governed by the setting of the forwarding crank 219. The punches and dies of the punch members 350, 351, respectively, may be made adjustable, if desired, to provide flexibility in their location angularly about the periphery of the punching cylinders and likewise laterally across the path of travel of the web.

From the punching unit 209 the web passes to the scoring or creasing or slitting devices 207, and thence to the feed rollers 204. The scoring devices may or may not be positively driven; if driven, they are preferably connected to the rack 223 through pawl and ratchet mechanism (not shown) so that they receive during the forwarding

event a movement depending upon the setting of the forwarding crank 219.

The feed rollers are actuated from the forwarding rack 223 through pawl and ratchet mechanism (not shown) during the forwarding even only, to feed the web toward the right to an extent depending upon the setting of the forwarding crank 219.

The shaft 354 of the cutting unit 210 is 10 likewise driven from the forwarding rack 223 through pawl and ratchet mechanism (not shown). This unit comprises a cylinder 356 keyed to the shaft 354, and is provided with peripheral T-shaped slots 357 15 affording means for retaining in their adjusted position the bolts 359 passing through these slots 357 and through apertures in curved blocks 360 which in turn carry the several rotating knives 362. The back or 20 non-cutting edge of each knife is held in position by a block 363 screwed to the curved blocks 360 as indicated in Figure 16. The setting of each knife radially of the cylinder 356 is effected by means of a screw 365 25 rounded by a compression spring 366, which tends to press the knife upwardly against the head of the screw. By tightening or loosening the screw 365, the knife 362 associated therewith may be moved toward or away 30 from the axis of the cylinder 356, and thus its position with respect to the fixed knife 367 may be accurately adjusted. The fixed knife is mounted upon a portion of the frame of the unit, and it may be adjusted 35 toward and away from the rotating knives 362 by means of the set screw 369.

In operation, the cutting cylinder 356 is 40 rotated during the forwarding event, to cut the web into suitable lengths after the other operations thereon have been completed, and is rotated during the return event to bring the knives into position for the next forwarding event. A preferred arrangement of parts is indicated in Figures 23 to 45, 26, wherein the cutting cylinder 356 is shown as rotating three-fourths of a complete revolution during each forwarding event. At the beginning of the forwarding event, rotation is imparted to the cylinder 50 simultaneously with the beginning of the paper movement. If the paper is to be cut into three lengths during each forwarding movement, as indicated in Figures 23 to 26, the paper is moved through one-third 55 of its length per cycle during the time that the cylinder 356 rotates one-fourth of a revolution from its position shown in Figure 23, so that one-third of the paper length has traveled past the fixed knife 367 when 60 the first cutter 362^a of the three rotary knives reaches cutting position, as indicated in Figure 24. The first length of paper is then severed and dropped into the receiving tray 371, which was assumed to be empty at 65 the beginning of the event. After the sec-

ond fourth of a revolution of the cylinder 356 the second knife 362^b has reached cutting position and the paper has been fed two-thirds of its feed per cycle; at this moment the second knife 362^b cuts off the 70 second length of paper, as indicated in Figure 25. Upon the completion of the third fourth of the revolution of the cylinder 356 the third knife 362^c has reached cutting position and cuts off the third length of web, 75 leaving three lengths or sections of paper now in the receiving tray 371, as indicated in Figure 25. The parts reach this position at the end of the forwarding or paper-feeding event. During the return event the 80 cutting cylinder 356 is rotated by the return rack to the position indicated in Figure 26, which it will be noted is a duplicate of Figure 23. Then the operations are repeated, three lengths of paper being cut off 85 and deposited in the receiving tray 371 during each forwarding event.

By re-arranging the knives 362 and increasing or decreasing their number, the number and relative lengths of the sections 90 of web cut during each forwarding event may be adjusted at will.

The operation of the embodiment of the invention illustrated in Figures 2 and 11 to 26 may be conveniently summarized by considering separately the several units and then by considering separately the four events of the cycle of operations.

The supply unit, comprising the support 201 for the roll of paper 202 and the feeding device 203, serves to deliver the web at the proper speed and under the proper tension.

In the first printing unit 205 the paper is fed toward the right, and the printing couple 105 is rotated to effect printing, through the rightward movement of the forwarding rack 223 during the forwarding event. The printing, as indicated above, is done on the top or face of the web during its passage 110 through this unit 205. At the end of the forwarding event the tripping mechanism separates the cylinders of the printing couple. During the return event the printing couple is rotated by the return rack 247 115 in the same direction as the rotation during printing, but the plate is at this time out of contact with the web and the web is stationary. During the fourth or re-engaging event the impression cylinder 237 of the printing couple is again raised into operative position by the tripping mechanism.

In the second printing unit 206 the paper is likewise fed to the right during the printing movement of the printing couple, due to 125 the forwarding or rightward movement of the forwarding rack 223 in the forwarding event. The printing here is done on the top or face of the web, as in the prior unit 205. During the tripping event the printing 130

couple is separated; during the return event the printing couple is rotated by the return rack; and during the fourth or re-engaging event the impression cylinder of the printing couple is again raised in operative position by the tripping mechanism.

It has been pointed out that the mechanism mounted on the shaft 260 operates to lower simultaneously the impression cylinders 237 in the units 205 and 206 (Figure 10 11). For the purpose of simultaneously raising the corresponding impression cylinder in the unit 208, I may provide a similar mechanism (not shown in the drawings) which may also be driven from the shaft 260 but all of whose parts are reversed with respect to the mechanism illustrated in Figure 11.

In the punching unit 209 the punching members 350, 351 are rotated by the forwarding rack 223 during the forwarding event, simultaneously with the paper feed. During the tripping event, this punching unit is idle. During the return event, the 25 punches are brought into their proper positions for the next forwarding event. During the re-engaging event, the unit is idle.

In the creasing device 207 the web is scored longitudinally, or if preferred the 30 web may be slit longitudinally, during the forwarding event, while the paper is being moved toward the right. If power is to be used upon the scoring rolls, the power may be obtained from the forwarding rack 223 35 through pawl and ratchet mechanism. During the tripping, return and re-engaging events, this scoring device is idle, since it has no connection with the return rack 247.

At the feeding device 204 the paper is fed 40 toward the right during the forwarding event, by a pawl and ratchet driving connection between the feed rolls and the forwarding rack 223. During the tripping, return and re-engagement events this device is idle.

45 In the cutting unit the paper is fed toward the right during the forwarding event, simultaneously with the counter-clockwise rotation of the cutting cylinder 356. If, as indicated in Figures 23 to 26, the paper is to be cut into three equal lengths, the cutting knives 362 are spaced 90° around the circumference of the cutting cylinder. At the beginning of the forwarding event the knives are in the position indicated in Figure 55 23. At the end of the first third of the event, when the paper has been fed one-third of its length per cycle, the first knife 362^a is in cutting position as indicated in Figure 24, and severs the first length of paper, which 60 drops into the receptacle 371. At the end of the second third of the event, when the paper has been fed two-thirds of its length per cycle, the second knife 362^b is in position and severs the second length of paper. 65 And at the end of the forwarding event,

when the paper has been fed its entire length per cycle, the third knife 362^c is in position and severs the third length of paper, as indicated in Figure 25. During the return event, the cylinder is rotated to the position 70 shown in Figure 26.

Considering now the operations occurring during the first or forwarding event: The feeding device 204, operated from the forwarding rack 223, feeds the paper toward 75 the right through a distance determined by the setting of the forwarding crank 219. Simultaneously the forwarding rack 223 imparts to each of the printing couples of the printing units 205, 206, 208, a rotation to 80 effect printing, and causes the punching, scoring, and cutting units to perform their several functions.

During the second or tripping event the tripping mechanism actuated by the cam 320 85 and operating rod 327, separates the printing couples of the units 205, 206 and 208, to permit rotation of the cylinders of the couples without a corresponding movement of the web. During this event the paper feed is 90 idle and likewise the other auxiliary units are not in operation.

During the third or return event the return rack 247 imparts to the elements of the printing couples of the units 205, 206, 208, 95 the punching unit 209, and the cylinder of the cutting unit 210 a movement to bring them into position for the next printing operation. The paper feed and the other units are idle during this event. 100

During the fourth or re-engaging event the tripping mechanism brings the cylinders of the printing couples of the units 205, 206, 208 again into operative engagement. The paper feed and such of the auxiliary units 105 as require no rotation to position their parts for the next forwarding event, are idle during this event.

Obviously, one or both of the flat-bed units 5, 6, of Figure 1 can be combined with one or both of the rotary units 205, 206 of Figure 2, thus providing a method and apparatus for separating the elements of the rotary printing couple between successive printing operations, while the web is stationary and is being operated upon by the flat-bed mechanism, and such a press is illustrated in Figure 27. This composite press combines the units 1, 5, and 6 of the press shown in Figure 1 with the units 205, 206, 208, 209, 207, 204, and 210 of the press shown in Figure 2. The drive for the latter group of units is shown, however, as the sector and rack drive of the press of Figure 1 rather than the link and sliding box drive of the press of Figure 2. Suitable mechanism is provided to also operate the flat-bed presses 5 and 6 and this may comprise mechanism similar to that shown 125 in the press of Figure 1. The details of the 130

units of this composite press are, in general, found in the presses of Figure 1 and Figure 2, and further description of this composite press, may, therefore, be omitted.

- 5 Similarly, a variety of other combinations of the several printing and auxiliary units in Figures 1 and 2 might be made without departing from the scope of the present invention, and some of these combinations are set forth in the accompanying claims. These alternative arrangements have not been illustrated, as their illustration would only complicate the drawings and would not add appreciably to the clearness 10 of the disclosure of the invention, since the rearrangements can be made readily with little or no modification of the structural features and relations of parts indicated in the drawings.
- 20 The word "unit" as used herein is usually intended to be generic to devices or apparatus for printing or for any of the various auxiliary operations, such as scoring, slitting, folding, punching, and cutting.
- 25 And the word "print" is ordinarily intended to include auxiliary operations as well as printing.

In view of the above, it is believed that the various features of this invention will 30 be clear without further elaboration, and it will be seen that with the apparatus and process herein disclosed the several objects of the invention are achieved and other advantageous results attained.

35 As various possible embodiments might be made of the above invention and as various changes might be made in the embodiments above set forth, it is to be understood that all matter herein set forth or shown in 40 the accompanying drawings is to be interpreted as illustrative and not in a limiting sense.

Having thus revealed my invention, I claim and desire to secure by Letters Patent 45 of the United States:

1. In apparatus of the class described, in combination, a supply device for delivering web, means for feeding the entire web intermittently, a flat-bed printing unit between 50 the supply device and the feeding means for operating upon the web while the entire web is stationary, a rotary printing unit between the supply device and the feeding means for operating upon the web while the entire 55 web is in motion, and means for rotating the printing couple of the latter unit while the entire web is stationary.

2. In apparatus of the class described, in combination, a printing unit comprising a 60 rotary printing couple, means for feeding a web through said unit and simultaneously rotating said couple to effect printing, and means for rotating said couple while the web is stationary.

3. In apparatus of the class described, in

combination, a rotary printing couple, means for feeding a web through said couple, means for simultaneously rotating said couple through a predetermined adjustable angular displacement, and means for rotating said couple through a predetermined adjustable angular displacement while the web is stationary.

4. In apparatus of the class described, in combination, a rotary printing couple, means 75 for feeding a web through said couple, means for simultaneously rotating said couple through a predetermined adjustable angular displacement, and separate means for rotating said couple through a predetermined adjustable angular displacement in the same direction, while the web is stationary.

5. In apparatus of the class described, in combination, a rotary printing couple, means 85 for feeding a web through said couple, means for simultaneously rotating said couple through a predetermined adjustable angular displacement, separate means for rotating said couple through a predetermined 90 adjustable angular displacement in the same direction while the web is stationary, and means preventing overthrow of said couple.

6. In apparatus of the class described, in combination, a rotary printing couple, gearing for rotating said couple through a predetermined adjustable angular displacement and for simultaneously feeding a web through said couple through a corresponding linear displacement to effect printing, 100 and gearing for rotating said couple while the web feed is inactive, to bring said couple into position for the next printing operation.

7. In apparatus of the class described, in combination, a rotary printing couple, gearing for rotating said couple through a predetermined adjustable angular displacement and for simultaneously feeding a web through said couple through a corresponding linear displacement to effect printing, 110 and gearing for continuing the rotation of said couple to bring said couple into position for the next printing operation, while the web feed is inactive.

8. In apparatus of the class described, in 115 combination, a source of power, a rack, gearing connected to said source of power and to said rack to reciprocate the latter, a printing couple, a device for feeding a web through said couple, gearing connecting said couple and said device with said rack to effect simultaneous feeding of the web and movement of the couple, a second rack, gearing connected to said source of power and to said second rack to reciprocate the latter, 120 and gearing connecting said couple with said second rack to effect movement of the couple.

9. In apparatus of the class described, in combination, a source of power, gearing connected to said source of power to be op- 125

- erated thereby through an adjustable distance, a printing couple, a device for feeding a web through said couple, means connecting said couple and said device with 5 said gearing to effect movement of the couple for printing upon the web, gearing connected to said source of power to be operated thereby, through an adjustable distance, and means connecting said couple 10 with said second gearing to effect movement of the couple, the sets of gearing being timed to actuate the couple alternately, so that the second gearing rotates the couple between successive printing operations.
- 15 10. In apparatus of the class described, in combination, a source of power, a rack, gearing connected to said source of power and to said rack to reciprocate the latter, a printing couple, a device for feeding a web through 20 said couple, gearing connecting said couple and said device with said rack to effect movement of the couple for printing upon the web, a second rack, gearing connected to said source of power and to said second rack 25 to reciprocate the latter, and gearing connecting said couple with said second rack to effect movement of the couple, the sets of gearing being timed to connect the racks to the couple alternately.
- 30 11. In apparatus of the class described, in combination, a source of power, a rack, gearing connected to said source of power and to said rack to reciprocate the latter through an adjustable distance, a printing couple, a 35 device for feeding a web through said couple, gearing connecting said couple and said device with said rack to effect simultaneous feeding of the web and movement of the couple, a second rack, gearing connected to said source of power and to said second rack to reciprocate the latter through an adjustable distance, and gearing connecting said couple with said second rack to effect movement of the couple in the same 40 direction as the movement effected by the first rack, the several sets of gearing being timed to connect the racks to the couple alternately, so that the second rack rotates the couple during the time that the web is stationary.
- 45 12. In apparatus of the class described, a shaft, a crank driven therefrom, means for adjusting the eccentricity of the crank, a gear, a connecting rod between the crank and the gear to oscillate the latter as the crank rotates, a rack meshing with said gear to be reciprocated as the crank rotates, a rotary printing couple, and mechanism connecting the rack in driving engagement with the 50 couple during the movement of the rack in one direction and disconnecting the rack from the couple during the movement of the rack in the other direction, the rack being so timed with the printing couple that the web is stationary during the movement of the rack in the other direction.
- 55 13. In apparatus of the class described, in combination, a shaft, a gear driven therefrom, a crank mounted on the gear, means for adjusting the eccentricity of the crank, a segmental gear, a connecting rod between the crank and the segmental gear to oscillate the latter as the crank rotates, a rack meshing with said segmental gear to be reciprocated as the crank rotates, a rotary printing couple, pawl and ratchet driving mechanism connecting the rack in driving engagement with the couple during the movement of the 60 rack in one direction and disconnecting the rack from the couple during the movement of the rack in other direction, a second gear driven from said shaft, a second crank mounted on said gear, means for adjusting the eccentricity of said second crank, a rack reciprocated by said second crank, and pawl and ratchet driving mechanism connecting said second rack in driving engagement with said couple during the movement of the rack in one direction and disconnecting the rack from the couple during the movement of the rack in other direction, the cranks being so timed with the pawl and ratchet mechanisms that the racks operate alternately upon the couple.
- 65 14. In apparatus of the class described, in combination, a shaft, a crank driven therefrom, means for adjusting the eccentricity of the crank, a gear, a connecting rod between the crank and the gear to oscillate the latter as the crank rotates, a rack meshing with said gear to be reciprocated as the crank rotates, a rotary printing couple, mechanism connecting the rack in driving engagement with the couple, during the movement of the rack in one direction and disconnecting the rack from the couple during the movement of the rack in the other direction, a second gear driven from said shaft, a second crank mounted on said gear, means for adjusting the eccentricity of said second crank, a rack reciprocated by said second crank, mechanism connecting said second rack in driving engagement with said couple during the movement of the rack in one direction and disconnecting the rack from the couple during the movement of the rack in the other direction, the cranks being so timed with the mechanisms that the racks operate alternately upon the couple, web-feeding rolls, and a pawl and ratchet mechanism connecting the first rack in driving engagement with said rolls during the movement of said rack in one direction and disconnecting said rack from said rolls during the movement of said rack in the other direction, said pawl and ratchet mechanism being arranged to feed the web during the movement of said couple by said first rack, the web being stationary during the movement of said couple by said second rack.
- 70 15. In apparatus of the class described, in combination, a web-delivering device, gearing, means for operating said gearing

through a predetermined stroke, other gearing, means for reciprocating said second gearing through a predetermined stroke, a web-feeding device, means connecting the 5 first gearing to said web-feeding device to impart to the web an intermittent feed, a printing unit operating upon the web when the web is stationary, a second printing unit, means connecting the first gearing to said 10 second unit during the paper-feeding stroke of said gearing only, to effect printing, means connecting the second gearing to said second unit during the non-feeding stroke of the first gearing, to operate said second unit, 15 and an auxiliary unit operating upon said web in synchronism with the operation of the printing units thereon.

16. In apparatus of the class described, in combination, a web-delivering device, gearing, means for operating said gearing through a predetermined stroke, other gearing, means for reciprocating said second gearing through a predetermined stroke, a web-feeding device, means connecting the 20 first gearing to said web-feeding device, to impart to the web an intermittent feed, a flat-bed printing unit operating upon the web when the web is stationary, a second printing unit comprising a rotary 25 couple, means connecting the first gearing to said couple during the paper-feeding stroke of said gearing only, to effect printing, means connecting the second gearing to said couple during the non-feeding stroke 30 of the first gearing, to impart to said couple an additional rotation, a cutting device operating upon the web after the web has passed through said feeding means, and means for driving said cutting device from 35 said first gearing during the paper-feeding 40 stroke of said gearing.

17. In apparatus of the class described, in combination, a web-delivering device, a rack, means for reciprocating the rack through 45 an adjustable stroke, a second rack, means for reciprocating said second rack through an adjustable stroke, a web-feeding device, gearing connecting the first rack to said web-feeding device to impart to the 50 web an intermittent feed of adjustable extent, a flat-bed printing unit operating upon the web when the web is stationary, a second flat-bed printing unit operating upon the web when the web is stationary, a third 55 printing unit comprising a rotary couple, gearing connecting the first rack to said couple during the paper-feeding stroke of said rack only, to effect printing, gearing connecting the second rack to said couple during the non-feeding stroke 60 of the first rack, to rotate said couple, and an auxiliary unit operating upon said web in synchronism with the operation of the 65 printing units thereon.

18. In apparatus of the class described, in combination, a web-delivering device, a 125 rack, means for reciprocating the rack, a second rack, means for reciprocating said second rack, a web-feeding device, gearing connecting the first rack to said web-feeding device to impart to the web an intermit- 130

cutting device from said first rack during the paper-feeding stroke of said rack.

18. In apparatus of the class described, in combination, gearing driven from a source of power, a plurality of units operating upon a web, mechanism connecting said units to said gearing to operate said units from said gearing, other gearing driven from said source of power, and mechanism connecting certain of said units to said second 70 gearing for operation from said gearing, the two sets of gearing being timed to operate alternately.

19. In apparatus of the class described, in combination, gearing driven from a source of power, a plurality of units operating upon a web, mechanism connecting said units to said gearing to operate said units from said gearing while said gearing is moving in one direction, other gearing 85 driven from said source of power, and mechanism connecting certain of said units to said second gearing for operation from said gearing while said gearing is moving in one direction, the two sets of gearing 90 being timed to operate alternately.

20. In apparatus of the class described, in combination, a source of power, oscillating gearing driven therefrom, a web-feeding device, a plurality of units operating upon said web, mechanism connecting said units and the web-feeding device to said gearing to operate said units from said gearing while said gearing is moving in one direction only, other oscillating gearing 95 driven from said source of power, and mechanism connecting certain of said units to said second gearing for operation from said gearing while said gearing is moving in one direction only, the two sets of gear- 100 ing being timed to operate alternately.

21. In apparatus of the class described, in combination, a web-delivering device, a rack, means for reciprocating the rack, a second rack, means for reciprocating said 110 second rack, a web-feeding device, gearing connecting the first rack to said web-feeding device to impart to the web an intermittent feed, a printing unit comprising a rotary couple, gearing connecting the first 115 rack to said couple during the paper-feeding stroke of said rack only, to effect printing, gearing connecting the second rack to said couple during the non-feeding stroke of the first rack, to rotate said couple, and an auxiliary unit operating upon said web in synchronism with the operation of the 120 printing units thereon.

22. In apparatus of the class described, in combination, a web-delivering device, a 125 rack, means for reciprocating the rack, a second rack, means for reciprocating said second rack, a web-feeding device, gearing connecting the first rack to said web-feeding device to impart to the web an intermit- 130

- tent feed, a plurality of printing units each comprising a rotary couple, gearing connecting the first rack to said couples during the paper-feeding stroke of said rack only, to effect printing, and gearing connecting the second rack to said couples during the non-feeding stroke of the first rack, to impart to said couples an additional rotation in the same direction.
23. In apparatus of the class described, in combination, a web-delivering device, a rack, means for reciprocating the rack through an adjustable stroke, a second rack, means for reciprocating said second rack through an adjustable stroke, a web-feeding device, gearing connecting the first rack to said web-feeding device to impart to the web an intermittent feed of adjustable extent, a plurality of printing units each comprising a rotary couple, gearing connecting the first rack to said couples during the paper-feeding stroke of said rack only, to effect printing, gearing connecting the second rack to said couples during the non-feeding stroke of the first rack, to impart to said couples an additional rotation, and a rotary cutting unit driven from the first rack during the paper-feeding stroke of said rack, to cut the web into lengths.
24. In apparatus of the class described, in combination, a web-delivering device, a rack, means for reciprocating the rack, a second rack, means for reciprocating said second rack, a web-feeding device, gearing connecting the first rack to said web-feeding device to impart to the web an intermittent feed, a printing unit comprising a rotary couple, gearing connecting the first rack to said couple during the paper-feeding stroke of said rack only, to effect printing, gearing connecting the second rack to said couple during the non-feeding stroke of the first rack, to rotate said couple, a cutting device operating upon the web after the web has passed through said feeding device, and means for driving said cutting device from said first rack during the paper-feeding stroke of said rack.
25. In apparatus of the class described, in combination, a plurality of rotary printing couples, gearing for rotating said couples through a predetermined adjustable angular displacement and for simultaneously feeding a web through said couples through a corresponding linear displacement to effect printing, and gearing for continuing the rotation of said couples to bring said couples into position for the next printing operation, while the web feed is inactive.
26. In apparatus of the class described, in combination, a rotary printing couple, means for rotating said couple to effect printing, means for separating the elements of said couple to permit independent movement of couple and paper, and means for
- rotating said couple when its elements are thus separated.
27. In apparatus of the class described, in combination, a rotary printing couple, means for rotating said couple to effect printing, means for separating the elements of said couple automatically upon the completion of each printing operating, to permit independent movement of couple and paper, and means for rotating said couple when its elements are thus separated.
28. In apparatus of the class described, in combination, a rotary printing couple, means for rotating said couple to effect printing upon a web between the elements thereof, means for feeding said web intermittently, means for separating the elements of said couple to permit independent movement of couple and web, and means for rotating said elements when the elements are thus separated and while the web is stationary.
29. In apparatus of the class described, in combination, a rotary printing couple, means for rotating said couple to effect printing upon a web between the elements thereof, means for feeding said web, means for separating the elements of said couple automatically upon the completion of each printing operation to permit independent movement of couple and web, and means for rotating said elements when the elements are thus separated and while the web is stationary.
30. In apparatus of the class described, in combination, means for feeding a web intermittently, a flat-bed printing couple operating upon the web while the web is stationary, a rotary printing couple operating upon the web while the web is in motion, and means for separating the elements of the rotary printing couple upon the completion of the web movement.
31. In apparatus of the class described, in combination, means for feeding a web intermittently, a flat-bed printing couple operating upon the web while the web is stationary, a rotary printing couple operating upon the web while the web is in motion, means for separating the elements of the rotary printing couple upon the completion of the web movement, and means for rotating said elements between successive web movements.
32. In apparatus of the class described, in combination, a flat-bed printing couple operating upon a web, a rotary printing couple operating upon the same web, and means for separating the elements of the rotary couple upon the completion of the printing operation thereof, for rotating said elements while the web is stationary, and for re-engaging said elements upon the completion of the latter rotation.
33. In apparatus of the class described, in

combination, a supply device for delivering web, means for feeding the web intermittently, a flat-bed printing couple between the supply device and the feeding means for operating upon the web while the web is stationary, a rotary printing couple between the supply device and the feeding means for operating upon the same web while the web is in motion, means for separating the elements of the rotary couple upon the completion of the web-feeding movement, and means for rotating said elements while the web is stationary, the second means acting to re-engage said elements upon the completion of the latter rotation.

34. In apparatus of the class described, in combination, a printing couple, means for feeding a web through said couple, means for rotating said couple to effect printing, means for rotating said couple between printing operations, to bring said couple into position for the next printing operation, and a tripping device automatically acting to separate the elements of the couple during said latter rotation.

35. In apparatus of the class described, in combination, a roll-fed printing couple, means for feeding a web through said couple and simultaneously rotating said couple to effect printing, means for rotating said couple while the web is stationary, to bring said couple into position for the next printing operation, and a tripping device automatically acting to separate the elements of the couple during said latter rotation.

36. In apparatus of the class described, in combination, a roll-fed printing couple, means for feeding a web through said couple and simultaneously rotating said couple to effect printing, means for rotating said couple while the web is stationary, to bring said couple into position for the next printing operation, and a tripping device automatically acting to separate the elements of the couple upon the completion of each printing operation and to re-engage said parts prior to the next printing operation.

37. In apparatus of the class described, in combination, a rotary printing couple, means for separating the elements thereof to permit independent movement of said elements and the web therebetween, a device acting automatically before and after each printing operation, and a handle operable to connect said device to said means to separate said elements upon the completion of each printing operation and to re-engage said elements prior to the next printing operation.

38. In apparatus of the class described, in combination, a rotary printing couple, means for separating the elements thereof to permit independent movement of said elements and the web therebetween, a device

acting automatically before and after each printing operation, and a handle operable to one position to connect said device to said means to separate said elements upon the completion of each printing operation and to re-engage said elements prior to the next printing operation, said handle operable to another position to disconnect said means from said device and permit manual movement of said means.

39. In apparatus of the class described, in combination, a rotary printing couple, means for separating the elements thereof to permit independent movement of said elements and the web therebetween, a device acting automatically before and after each printing operation, and a handle operable to one position to connect said device to said means to separate said elements upon the completion of each printing operation and to re-engage said elements prior to the next printing operation, said handle operable to another position to disconnect said means from said device and permit manual movement of said means, said handle operable to a third position to lock said couple in engagement.

40. In apparatus of the class described, in combination, a source of power, a cam revolved thereby, a rod raised and lowered by the cam, a rocking member operated by the rod, a shaft, a toggle operated thereby, a printing couple, one member of which is mounted for reciprocation toward and away from the other member in accordance with the movement of said toggle, and means for connecting said shaft to said rocking member to trip and re-engage said printing couple by the operation of said cam, said last-named means being shiftable to permit manual tripping and re-engaging of the couple independently of said cam, and being further shiftable to lock said couple in engaged position independently of the movement of said cam.

41. In apparatus of the class described, in combination, a rotary printing couple, means for feeding a web therethrough and for simultaneously rotating said couple to effect printing, a cutting unit, means for operating said unit during the feeding of the web to sever the web into lengths, and means for rotating the printing couple between successive printing operations.

42. In apparatus of the class described, in combination, a rotary printing couple, means for feeding a web intermittently therethrough and for simultaneously rotating said couple to effect printing, a rotary cutting unit, means for rotating said unit during the feeding of the web to sever the web into lengths, and means for imparting to the printing couple a rotation between successive printing operations, while the web is stationary.

43. The method of printing, which comprises passing a web through a flat-bed printing unit and printing upon the web while the web is stationary therein, passing the same web through a rotary printing unit and printing upon the web while the web is in motion therein, and separating the elements of the printing couple of the rotary printing unit and moving said elements while the web is stationary, to bring said couple into position for the next printing operation.
44. The method of printing, which comprises passing a web through a flat-bed printing unit and through a rotary printing unit, printing upon the web at the flat-bed unit while the web is stationary, printing upon the web at the rotary unit while the web is in motion, separating the members of the rotary printing couple upon the completion of each web feed, rotating said members while the web is stationary, and re-engaging said members prior to the next web feed.
45. In apparatus of the class described, in combination, a printing couple, a pawl-and-ratchet drive therefor, and means for locking the pawl and ratchet against relative rotation.
46. In apparatus of the class described, in combination, a printing couple, a pawl-and-ratchet drive therefor, and means for positively locking the pawl and ratchet against relative rotation while the pawl is in driving engagement with the ratchet.
47. In apparatus of the class described, in combination, a printing couple, an intermittently operating pawl-and-ratchet drive therefor, and means for automatically locking the pawl and ratchet against relative rotation during each driving operation and for permitting relative rotation of pawl and ratchet between successive driving operations.
48. In apparatus of the class described, in combination, a rotary printing couple, pawl-and-ratchet mechanism adapted to drive said couple from a prime mover during the paper-feeding event of the cycle of operation, and to permit rotation of the printing couple independently of the prime mover between successive paper-feeding events, a pin slidable in one of the elements of said mechanism, a hole in the other element registering with said pin when the pawl is properly in engagement with the ratchet, and means for moving the pin into said hole automatically at the beginning of each paper-feeding event and for removing the pin from said hole automatically at the end of each paper-feeding event.
49. In apparatus of the class described, in combination, a printing couple, a pawl-and-ratchet drive therefor, a reciprocating member, a pin in one of the elements of said drive adapted to enter a hole in the other element of the drive, and resilient connections between said member and said pin, for moving the pin into the hole at the beginning of the paper-feeding event to connect said elements together positively, and for moving the pin out of the hole at the end of the paper-feeding event, to disconnect said elements.
50. In apparatus of the class described, in combination, a rotary printing couple, a pawl-and-ratchet drive therefor, a member supporting the pawl, a member supporting the ratchet, a pin movable in one of said members and adapted to register with a hole in the other member when the pawl and ratchet are in engagement, and means for blanketing said hole when the pawl is not in engagement with the ratchet.
51. In apparatus of the class described, in combination, a rotary printing couple, and pawl-and-ratchet drive therefor, a member supporting the pawl, a pin slidable in said ratchet and adapted to register with a hole in the pawl-supporting member when the pawl is in engagement with said ratchet, and an extension on the pawl adapted to blanket said hole when the pawl is not in engagement with the ratchet.
52. In apparatus of the class described, in combination, a rotary printing couple, a ratchet revoluble therewith, a pawl adapted to engage the ratchet to drive said couple, a member supporting the pawl, a pin slidable in said ratchet and adapted to register with a hole in the pawl-supporting member when the pawl is in engagement with said ratchet, an extension on the pawl adapted to blanket said hole when the pawl is not in engagement with the ratchet, and means for moving said pin automatically into said hole at the beginning of each paper-feeding event.

In testimony whereof, I have signed my name to this specification this 29th day of September, 1917.

GEORGE R. WILLIAMS.
